Design for Server by John George Tag N.Y.
assigned to Morrison & Tidbits of same place

Patented April 13, 1852.

Des. 45

John G. Savage of Troy, N.Y.
Assigned to Alex. Morrison & Thos. M. Gibbets of same place
Letters Patent No 451 Dated April 13. 1852

The schedule referred to in these Letters Patent and making part of the same

To all whom it may concern,

Be it known that John G. Savage of the City of Troy county of Rensselaer and State of New York have invented or produced a new and original design for ornamenting the plates & doors of cooking stoves - which stove I distinguish by the name of the "New York and Erie" and I do hereby declare that the following is a full and exact description of the same, reference being had to the accompanying drawing making a part of this specification in which A is the drop oven door, the panel of which is ornamented with a locomotive engine, tender and passenger car represented as being in motion B is the swing oven door the panel of which is ornamented with a locomotive engine, tender and passenger car, crossing a bridge and river. C is an ornamental raised panel on the jamb. D. E is the fire door ornamented on the panel with a Romanesque rossette F. G is one of the front doors the panel of which is ornamented with the rossette H. I is the front plate ornamented on the panel with the centre piece K. L is the base moulding decorated alternately with the ornaments (m) and (n) around the whole base. O is the leg ornamented on the face with the rossette P. Q is the top plate ornamented around the moulding with the rope work R.

Having thus described my design what I desire to secure by letters patent is the configuration of and ornamenting the plates and panels of cooking stoves substantially the same as herein represented and set forth.

Exd,
J. O'B.
